US00D894942S

(12) **United States Design Patent** (10) **Patent No.:** **US D894,942 S**
(45) **Date of Patent:** **** Sep. 1, 2020**

(54) **ELECTRONIC DEVICE WITH GRAPHICAL USER INTERFACE**

(71) Applicant: **Apple Inc.**, Cupertino, CA (US)

(72) Inventors: **Christopher P. Foss**, San Francisco, CA (US); **Nicholas V. King**, San Jose, CA (US); **Stephen O. Lemay**, Palo Alto, CA (US); **Richard D. Lyons**, San Francisco, CA (US); **Charmian Naguit**, Richmond, CA (US); **Matthew J. Sundstrom**, Campbell, CA (US); **Christopher I. Wilson**, San Francisco, CA (US)

(73) Assignee: **Apple Inc.**, Cupertino, CA (US)

(**) Term: **15 Years**

(21) Appl. No.: **29/692,905**

(22) Filed: **May 29, 2019**

(57) **CLAIM**

The ornamental design for an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; FIG. 2 is another embodiment thereof; and,

FIG. 3 is a front view of an electronic device having a display screen with the graphical user interface of FIG. 1 applied thereto. The graphical user interface design of FIG. 2 may be similarly applied thereto.

The broken lines in the figures show a display screen or portion thereof, or an electronic device having a display screen, and form no part of the claimed design.
